UNITED STATES PATENT OFFICE.

MELBERN BERNIE BULLA, OF EL PASO, TEXAS.

AUTOMATIC TRAIN-SIGNAL.

1,285,556.

Specification of Letters Patent. Patented Nov. 19, 1918.

Application filed October 22, 1917. Serial No. 197,914.

To all whom it may concern:

Be it known that I, MELBERN B. BULLA, a citizen of the United States, and a resident of El Paso, in the county of El Paso and State of Texas, have invented a new and Improved Automatic Train-Signal, of which the following is a full, clear, and exact description.

This invention relates to safety appliances for railways and has particular reference to automatic track appliances serving either to give indications of signals to the locomotive driver or to insure the operation of automatic train stops, although the braking or stopping mechanisms that may be relied upon are not indicated in this particular instance.

More definitely stated my improvement relates especially to a railway track safety brush. I distinguish from an auxiliary rail, ramp, or other track obstruction, whereby I am more certain of securing proper operation of the electric devices when the track is covered with snow, ice, sand, or other materials which are so apt to prevent the proper operation of other types of automatic signaling devices.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a diagram showing my improved track devices in relation to the meeting ends of adjacent rails.

Fig. 2 is a diagram in plan showing my improvement in connection with an electric signal; and

Fig. 3 is a horizontal sectional detail on the line 3—3 of Fig. 1.

Referring now more particularly to the drawings, for an understanding of the mechanism, I show at A and B the adjacent rails of two adjacent railway blocks and at C is a semaphore which is to be taken as typifying any suitable signal devices used in connection with a railway.

At 10 I show a brush representing an electric contact member adjacent the track which when deenergized because of danger

ahead will serve to actuate certain devices carried by the locomotive or other parts of the train for stopping the train or giving such signals to the trainmen as may be requisite, such features not constituting any part of the present invention. The brush 10 is supported upon a base 11 of insulation through which the bonding wires 12 leading from one rail to the other are threaded. It follows, therefore, that in the event of the brush being torn from its place by a brake or anything that should be dragging from a train passing thereover, the bonding wires normally connecting the adjacent rails of adjacent blocks, will be torn asunder.

At 13, I show a battery in a circuit 14 and in this circuit is arranged a relay 15 having an armature 16 pivoted at 17. When the circuit is broken either because of the disconnection of the contacts 18 by the setting of the semaphore to danger position or because of the failure of the circuit or battery or any other reason, the armature 16 will gravitate to the position shown in Fig. 1 where it makes contact with a contact member 19 bonded through a post 20 and wires 12 to rail A. The brush, therefore, is given a metallic connection through a shank 21, support 22, and the parts just above described with the rail A, the shank 21 being in metallic contact at its upper end with the brush, as shown. It will be seen, therefore, that when an on-coming train attempts to pass the danger signal, some suitable device on the locomotive will make contact with the brush and complete a circuit through the rail and wheels to apply the brakes or perform such other functions as may be desired to prevent an accident. When, however, the block signal is clear and the contacts 18 are reconnected, the relay will be energized and break the connection between the armature 16 and the contact point 19. At this time the brush being supported upon its base 11 and so insulated from the bonding wires 12, will be electrically disconnected from the rail A, and the train devices will not be affected. This operation just described is predicated upon the fact that the battery 13 and circuit 14 are in perfect condition. Should they fail, however, for any reason the brush will automatically be brought into metallic connection with the rail A and will stop an oncoming train whether the track ahead be clear or not. As indicated in Fig. 3, the bonding wires 12 pass through the block or

base of insulation 11 out of contact with the shank 21, while the post 20 is connected metallically with the rail A through said bonding wires.

5 In Fig. 2 I indicate my improvement as applied to an electric signal of any known or suitable type, the same including a signal lamp C' arranged in a circuit 23 having a battery 24. Associated with this circuit is another circuit 25, in which is a relay 26. An armature 27, when the track is clear, is held up by the relay 26, but when the signal is set at danger, said armature 27 drops to close the circuit 23 by engaging the contact 28. The armature 27 carries a contact 29 coöperating with a pair of contacts 18' pertaining to a circuit 14 similar to that already described in connection with Fig. 1. When the track is clear and the armature 27 is attracted by the relay 26, the contacts 29 and 18' close the circuit 14, and thereby the armature 16 is held up by the magnet 15.

25 In the practice of my invention the track circuit is carried from one rail to the other through the bonding wires which extend through the base of the brush. The object of running the bonding wires directly through the insulated base of the brush is to insure that in case the brush is torn out of place the action will be just the same as a broken rail and hence the block signals will be set at red on both sides of it which will, of course, result in the stopping of a train approaching from either direction. The insulated joint makes this result positive, but a broken rail does not always do this because it sometimes happens that a rail may be broken and the ends not separated far enough to break the circuit.

30 35 40 Copies of this patent may be obtained for five cents each, by addressing the "Commissioner of Patents, Washington, D. C."

I claim:

1. In a train signal appliance, the combination of a pair of railway rails, bonding means extending from one rail to the next, an electric contact brush, a support for the brush adjacent to the joint between the rails, said support including a base of insulation, said bonding means passing through said insulation base whereby the brush is immovable from the rail joint without disturbing the bonding means, a relay adjacent to the base, a normally closed circuit in which the relay is positioned, signal means serving to break said circuit when set at danger, and means whereby the breaking of the circuit through the relay will bring the brush into electric connection with one of the rails.

2. In a railway signal appliance, the combination with two adjacent railway rails insulated from each other and bonding means extending from one to the next, of a block of insulation through which said bonding means extends, an electric brush supported upon said block and thereby insulated from the bonding means, supporting means for the block including a post having metallic connection with the bonding means, said supporting means also including a contact post having a shank extending through the block into metallic connection with the brush but insulated from the bonding means, a relay adjacent to the block, an armature for the relay normally bridging the space between the two posts aforesaid bringing the brush into electric connection with one of the rails, and signaling means serving to energize the relay so as to break the electric connection between the brush and the rail aforesaid.

MELBERN BERNIE BULLA.
